UNITED STATES PATENT OFFICE.

ALBERT B. WEISSENBORN, OF APPLETON, WISCONSIN, ASSIGNOR TO SCOLDING LOCKS HAIRPIN COMPANY, OF APPLETON, WISCONSIN.

WIRE-FEEDING MECHANISM.

Application filed October 9, 1925. Serial No. 61,469.

This invention relates to improvements in means for feeding wire to any preferred operating mechanism, and is more particularly designed for use in connection with machines for forming wire hairpins, as disclosed in Patent No. 1,309,660, issued July 15, 1919, wherein is disclosed a reciprocating wire feeding mechanism for intermittently feeding wire to the various forming mechanisms.

The invention has for its primary object the provision of a mechanism of the foregoing character, which is both positive and rapid in its feeding action, whereby the capacity of the mechanism, to which the wire is fed, is materially increased.

A further object is to provide an intermittent feeding mechanism which will not vary the length of wire fed during each operation.

With the above and other objects in view, which will appear as the description proceeds, the invention resides in the novel construction, combination and arrangement of parts, substantially as hereinafter described and more particularly defined by the appended claims, it being understood that such changes in the precise embodiment of the herein disclosed invention may be made as come within the scope of the claims.

In the accompanying drawing is illustrated one complete example of the physical embodiment of the present invention constructed according to the best mode so far devised for the practical application of the principles thereof.

Figure 1 is a longitudinal sectional view through a mechanism constructed in accordance with one form of the present invention, the same being taken on the lines 1—1 of Figures 2 and 3.

Figure 2 is a transverse sectional view taken on the line 2—2 of Figure 1, and

Figure 3 is a plan section taken on the line 3—3 of Figure 1.

That form of the present invention illustrated in the drawings is designed for use in connection with a hairpin forming machine, in which a table 1 is utilized, the same being provided with an aperture 2 for the feeding mechanism about to be described.

Secured upon the table 1 adjacent the aperture 2 are a pair of brackets 3 and 4, the major portion of which extend above the table, while an arm 5 projects through the aperture and below the table 1 to serve

as a bearing for the mechanism carried by the brackets. The bracket 4 is provided with a base 6 which is rigidly secured to the top of the table by means of the bolt 7, while the bracket 3 is pivotally mounted upon the stud 8 carried by the table.

Both brackets are provided with a pair of vertical arms 9 in which are formed bearings for the reception of the longitudinal horizontal shafts 10, having secured to one end the spur gears 11 which mesh with the gear 12 carried by the main driven shafts 13 of a hairpin machine, which shaft is mounted above the brackets 3 and 4 and extends throughout the entire length of the machine for actuating the various forming mechanisms, not shown.

The brackets 3 and 4 are provided with lateral extensions 14 which cooperate with the arms 5 to form suitable bearings for the vertical shafts 15 which are geared to the driven shafts 10 by means of the beveled pinions 16 arranged to rotate each of the shafts 15 in opposite directions.

Secured on the shafts 15 adjacent the top of the table 1 are a pair of respective feeding discs 17 and 18, the peripheral faces of which cooperate with one another for the purpose of engaging the wire W and intermittently feeding the same a predetermined length during each operation. In order to accomplish this the peripheral faces of both discs are provided with a plurality of annular grooves 19 of different size, for selective use in connection with various gauges of wire.

Clamping engagement of the wire between the faces of the discs 17 and 18 is maintained by means of a bolt 20, the ends of which are secured to the lateral extensions 14 of the brackets 3 and 4, by means of nuts 21 threaded on the bolts on opposite sides of the brackets.

Due to the fact that the bracket 4 is rigidly secured to the table 1, while the bracket 3 is pivotally mounted thereon, it is obvious that their desired relative position can be maintained by running the nuts 21 in or out upon the bolt 20. By this arrangement considerable tension can be exerted upon the wire gripped between the faces of the discs 17 and 18, thus insuring positive feed during the feeding operation of the discs.

In order to obtain an intermittent feed essential in a hairpin forming machine where

squarely against the inner or bottom wall of the said socket. The operator then uses a hammer, striking the outer plug in the direction of the length of the axle whereby the wheel is jarred loose from the axle and the key thereof and may be quickly removed.

Having described the invention what is claimed is—

A device adapted to be used for removing a wheel from an axle upon which it is keyed comprising a body provided at its opposite ends with alined sockets of different sizes, and anvil plugs fitting in the sockets.

In testimony whereof I affix my signature.

CASH A. CLEMONS.
